CLAIM

The ornamental design for a packaging spike, as shown and described.

DESCRIPTION

FIG. 1 is a front-top perspective view of a packaging spike in accordance with my new design;

FIG. 2 is a rear-top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top view thereof; and,

FIG. 8 is a bottom view thereof.

The symbolic breaks shown in the drawings indicate that any appearance of any portion of the article between the break lines forms no part of the claimed design.
